Inventor,
Harry Krasnow,
Frank S. Ahlmann,
By

Attorney

UNITED STATES PATENT OFFICE.

HARRY KRASNOW, OF HARTFORD, CONNECTICUT.

METAL BUILDING STRUCTURE.

Application filed August 29, 1922. Serial No. 585,028.

To all whom it may concern:

Be it known that I, HARRY KRASNOW, a citizen of Russia, and resident of Hartford, in the county of Hartford and State of Connecticut, have invented certain new and useful Improvements in Metal Building Structures, of which the following is a specification.

This invention relates to metallic building structures, and particularly to columns or like elements, and the said invention relates particularly to novel means for providing columns of the character indicated with brackets or beam supports, although auxiliary thereto. Provision is made for supplying the column with a cap plate having novel means by which it is anchored and associated with beam or girder engagement elements.

It is primarily a part of this invention to provide a column of the character indicated comprising a cylindrical metallic shell having a composition filling such as concrete or the like, brackets being also provided whereby beams or girders may have their ends supported in stepped relation to each other on the column; and the invention comprises other features which results in an advantage as to the stability of the structure and the facility with which the parts can be assembled, in addition to the latitude allowed in the manner of bearing or supporting surfaces, so that proportions may be changed to suit particular requirements without necessitating change in the fundamental structure of the device.

It is a further object of this invention to provide a bracket, the base of which is shaped to the curved contour of the outer wall of the said casing.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a view in elevation of the upper end of a column showing the same equipped with column supporting devices embodying the invention;

Figure 2 illustrates a sectional view on the line 2—2 of Fig. 1;

Figure 3 illustrates a vertical sectional view thereof;

Figure 4 illustrates a perspective view of 60 the cap plate inverted;

Figure 5 illustrates a perspective view of the column with the cap plate removed;

Figure 6 illustrates a view in elevation of the upper end of a column showing a girder 65 in section;

Figure 7 illustrates a view in elevation showing fragments of two sections of a column with fastenings for anchoring one on the other; and

Figure 8 illustrates a view in elevation showing the application of the invention to a fragment of a building.

In these drawings 10 denotes the shell of the column, 11 the concrete composition filling for the same. In the present embodiment of the invention, the column supports comprise 7-shaped brackets, the bases 12 of which are curved to the contour of the shell and are intended to fit closely thereagainst 80 when they are secured in place by fastenings 13 such as rivets or the like. The inventor does not wish to be limited with respect to the fastenings, and under certain conditions, bolts could be employed and, of course, the shape of the head of the rivet is immaterial. The web 14 of each bracket may extend outwardly from the base to any appropriate degree, depending upon the area desired for the support of the beam. 90

Preferably at the upper end of each web, angle plates 15 are secured to the sides of each web, and the flange of the angle plate which is not secured to the web has its outer face in alignment with the upper edge of the web, and by this construction, a relatively wide base or support for the I-beam or girder will be provided. Of course it will be understood that the area or sizes of the supporting flanges of the angle plates may be 100 increased or diminished to suit particular requirements. It will also be understood that the number of brackets may be increased or diminished, according to the number of beams to be supported, and their positions with relation to the periphery of the column may be made to accord with the direction which the beam is to extend from the column.

In order to increase the sheer resisting ef- 110

fect in the construction, a reinforcing plate 16 may be applied to the interior of the shell where each of the brackets is to be attached. When these plates are added, the fastenings 5 or rivets will, of course, project through them and they will be secured in place simultaneously with the fastening of the flanges of the brackets.

The cap plate 17 may be secured in place 10 in two ways, as illustrated. One of the means consists in providing the cap plate with apertures 18 to receive fastenings 19 that extend therethrough and through the flanges of the angle irons; and the other 15 method contemplates the use of flanged elements 20 that are secured to the under side of the cap plate, the said flanged elements having lips 21 that engage cleats 22 applied to the interior of the shell, in the present 20 embodiment of the invention, in contact with the reinforcing plates, and they may be secured by the same fastenings which are employed for fastening the reinforcing plates. In some constructions, the reinforcing 25 plates will be omitted perhaps, and in that event, cleats will be secured against the inner surface of the column. For most purposes, two cleats and two engaging elements carried by the cap plate will be employed, and when the cap plate is secured to 30 the column, the cleat engaging elements will be out of alignment with the cleats, and then by turning the cap plate, there will be an interlocking engagement between the cleats 35 and the engaging elements, and when the shell is filled with set concrete, the parts will be held in proper positions.

In some structures, the cap plate will be omitted, and in that event, the flanges of 40 I-beams may be secured directly to the flanges of the angle irons by appropriate fastenings such as rivets, and the inventor does not wish to be limited with respect to this application of the invention.

In Figure 8, a column is shown, associated with and supporting a relatively heavy I-beam 22^a, associated with a bracket 23 adapted to support a relatively lighter I-beam 24 wherein the supporting surfaces 50 of the two beams are on the same plane. In this construction, the bracket 23 has a web and flange that is longer than the web of the bracket which supports the I-beam 22^a. The illustration just described is furnished 55 for the purpose of illustrating the various ways by which the same invention may be used in practice, and, of course, other modifications as to proportions will present themselves to those skilled in the art. The bracket 23 may have a web longer or shorter 60 in order that it will support beams of other dimensions in the same relation to the beam 22 as that shown, and the number of brackets employed may also be varied to 65 suit particular requirements.

In Figure 7, a joint between two sections 25 and 26 of a column is illustrated, in which the brackets are of the same construction as those heretofore described, but in this construction, the flanges of the angle irons of one bracket are secured to the flanges of the angle irons of the superimposed section, and by this means, a continuous column is formed. Furthermore, 70 in this illustration, only two brackets of one section are shown as secured to two brackets of the other section, and an I-beam 27 is illustrated as being supported on the bracket of the lower section, and this illustration is provided to convey the idea that the brackets may be used either as a means for coupling sections together, or as a support for a beam.

It is also observed that the brackets on the lower section constitute what may be termed "caps," and the brackets on the lower end of the upper section may be regarded as bases, so that when the caps and bases are secured together, the structure is braced against lateral strain to a very 90 marked degree, the advantages of which will be apparent.

In the construction shown in Fig. 6, the brackets 28 constitute caps on which girder seats 29 may be secured in appropriate manner to retain girders 30 against displacement. The girder seats may be formed either of channel iron or angle irons, as those skilled in the art will understand.

The brackets are formed of steel, and the bases thereof are forged having a curve of the proper arc so that it will conform to the outer surface of the column to which the bases are to be applied.

I claim:

1. In a metal structure, a cylindrical shell, brackets comprising steel bases shaped to the contour of the outer surface of the shell and having webs projecting therefrom, angle irons secured to the webs at their outer edges and constituting supports, reinforcing plates on the inside of the shell, and fastenings extending through the bases of the brackets, the shell and the said reinforcing plates.

2. In a metal structure, a cylindrical shell, brackets comprising steel bases shaped to the contour of the outer surface of the shell and having webs projecting therefrom, angle irons secured to the webs at their outer edges and constituting supports, means for securing the said bases to the shell, cap plates for the column, cleats on the inside of the column, members carried by the cap plate adapted to interlock with the cleats, and a composition within the shell for holding the cap plate fastenings in place.
